His Attorney.

UNITED STATES PATENT OFFICE

2,515,747

LAMP BASE

Daniel J. Vaughan, Euclid, Ohio, assignor to General Electric Company, a corporation of New York

Application November 14, 1949, Serial No. 127,171

2 Claims. (Cl. 176—32)

1

My invention relates to lamp bases for electric lamps and similar devices and more particularly to electric lamps having elongated envelopes with bases at both ends which engage suitably spaced sockets.

In the U. S. Patent 2,338,835, issued January 11, 1945, to F. D. Bryant and assigned to the assignee of the present application, a supporting base for such lamps is disclosed and claimed as well as a socket for receiving the lamp base. The base described in the patent comprises an electrical contact-carrying body portion of insulating material, preferably porcelain, to which is secured a metal skirt for attaching the base to the elongated tubular glass or quartz envelope of the lamp. While bases of the type described in the patent have been successfully used for many years, they have not been entirely satisfactory due to the difficulty in providing a tight connection between the metal collar or skirt and the porcelain insulator forming the main body of the base.

Obviously, a tight connection between these parts is highly desirable in order to obtain proper mounting of the lamp in lighting fixtures and the like; and it is the principal object of the present invention to provide a strong, firm, tight connection between these base elements. Further objects and advantages attaching to the invention will be apparent from the following detailed description and from the accompanying drawing in which Fig. 1 is a perspective view of a lamp base embodying my invention and Fig. 2 is a partly sectional view of the base along the line 2—2 of Fig. 1 and showing one end of a lamp in full.

Referring to the drawing, the base 1 is mounted on an elongated tubular glass or quartz lamp envelope 2 which may contain an electrode in each end where the device is a discharge lamp or, in the case of an incandescent lamp, a filament extending longitudinally from end to end of the envelope. The base 1 comprises a body portion 3 of insulating material, preferably porcelain. The said body portion 3 is secured to the end of the envelope 2 by means of a metal skirt or collar 4 which is secured to an enlarged shoulder 5 on said body portion 3. Before the skirt 4 is slipped over the end of the tube 2, a thin strip 6 of asbestos paper moistened with a solution of sodium silicate is wrapped around the envelope 2. The skirt 4 is secured firmly in place on the envelope 2 by a suitable clamping strip 7, the skirt 4 being provided with a multiplicity of slits 8 therein so as to be readily compress-

2

ible by clamping strip 7 around the asbestos strip 6 and clamp the latter between the lamp envelope 2 and the clamp 7. The outer end 9 of the body portion 3 carries a spade-shaped metal electrical contact prong 10 which extends outwardly therefrom and longitudinally of the lamp envelope 2. The said prong 10 is electrically connected by a flexible conductor 11 to the end of a current lead-in wire 12 which extends through a seal 13 and is electrically connected to the electrode or filament (not shown) in the envelope 2. The conductor 11 extends through a longitudinal opening in the prong 10 and is soldered to the prong at its outer end.

15 The physical connection between the body portion 3 and the skirt 4 of the base of the present invention is different than the connection between these components of the patented base in which the skirt is provided with an annular depression, or bead, spaced inwardly longitudinally from the end of the skirt opposite the slit end thereof, the shoulder of the body portion is inserted in the said solid wall end of the skirt and held against the bead and the said solid 20 wall end portion of the skirt is crimped over the shoulder to clamp the shoulder in the skirt. Due to the difficulty of making porcelain bodies to close tolerances, the physical connection between the skirt and the porcelain body portion of the patented base was frequently loose and 25 therefore not entirely satisfactory.

In accordance with the present invention, the skirt 4 is tightly secured to the body portion 3 by a split metal snap ring 14 inside the skirt 4 which ring 14 is forced against the side 15 of the shoulder 5 of the body portion 3 and held in such position thereagainst by the four indentations or dimples 16 spaced 90° apart in the wall of the skirt 4. The bottom wall 17 of the skirt 4 is partially closed by an inwardly 30 extending flange 17' and coincides in form with and engages the side 18 of the shoulder 5 of the portion 3.

In assembling the base 1, the body portion 3 is passed through the end of larger diameter of the skirt 4 until the flange 17' of the partially closed bottom wall 17 of the skirt 4 engages the side 18 of the shoulder 5 of the body portion 3. The snap ring 14 is then placed and held in position against the side 15 of the shoulder 5 of the body portion 3 and the four dimples 16 are then punched in the wall of the skirt 4 to hold the ring 14 against the side 15 of the shoulder 5. The snap ring 14 serves as a cushion against the 40 shock of mechanical press assembly and, when 45 50 55

held in position by the dimples 16, maintains a pressure against the dimples 16 and against the shoulder 5 of the portion 3 sufficient to provide the desired tight physical connection between the skirt 4 and the body portion 3.

This structure and the method of assembling the base 1 permits rather large tolerances in the dimensions of the porcelain body portion 3 of the base 1, such porcelain bodies being difficult to make to close tolerances. The snap ring 14 compensates for any variation in the size of the body portion 3 within a reasonable range of size variation.

Relative rotary displacements between the body portion 3 and the skirt 4 are prevented by four depressed longitudinal slots 19 spaced 90° apart in the shoulder 5 of the body portion 3 of the base 1 into which fit inwardly and longitudinally extending ridges 20 in the wall 17 of skirt 4. The dimples 16 are spaced from the ridges 20 an angular distance of 45°, preferably. The slits 8 are made in the skirt 4 preferably after the skirt 4 and the body portion 3 have been secured together as described above.

What I claim as new and desire to secure by Letters Patent of the United States is:

1. A base for a double-ended electric lamp comprising a hollow tubular body portion of

electrically insulating material adapted to carry at one end an electrical contact and having a shoulder at its opposite end and a metal skirt overlapping and secured to said shoulder by an integral inward flange engaging one side of said shoulder and a split snap ring of metal held against the other side of said shoulder by radially spaced indentations in the wall of said skirt.

2. A base for a double-ended electric lamp comprising a hollow tubular body portion of electrically insulating material adapted to carry at one end an electrical contact and having a shoulder at its opposite end and a metal skirt overlapping and secured to said shoulder by an integral inward flange engaging one side of said shoulder and a split snap ring of metal held against the other side of said shoulder by radially spaced indentation in the wall of said skirt to hold said body portion and said skirt tightly together, said shoulder having longitudinally extending slots in its periphery and said skirt having longitudinally extending indentations fitting into said slots to hold said elements against relative rotary displacements.
